Specification for Design.

Patented Oct. 4, 1921.

Application filed September 23, 1920. Serial No. 412,399. Term of patent 3½ years.

To all whom it may concern:

Be it known that I, EDWARD C. PETERKE, a citizen of the United States, residing at Fairfield, in the county of Jefferson and State of Iowa, have invented a new, original, and ornamental Design for Portable Cases Having Compartments for Stationery Supplies, of which the following is a specification, reference being had to the accompanying drawing, forming part thereof.

The figure is a perspective view of a portable case having compartments for stationery supplies, showing my new design.

I claim:

The ornamental design for a portable case having compartments for stationery supplies, as shown.

Fairfield, Iowa, September 21st, 1920.

EDWARD C. PETERKE.
